UNITED STATES PATENT OFFICE.

HENRY L. DOHERTY, OF NEW YORK, N. Y.

METHOD OF BURNING LIQUID FUELS.

1,101,789.

Specification of Letters Patent. Patented June 30, 1914.

Application filed January 10, 1911. Serial No. 601,795.

To all whom it may concern:

Be it known that I, HENRY L. DOHERTY, a citizen of the United States, and a resident of New York city, in the county of New York and State of New York, have invented certain new and useful Improvements in Methods of Burning Liquid Fuels, of which the following is a specification.

This invention relates to methods of burning liquid fuels and, in particular, to methods of burning such fuels to produce a comparatively smokeless flame of moderate temperature.

The object of my invention is to so improve the present known methods of burning fuels of the class mentioned as to adapt them for the heating of kilns, furnaces, etc., in which flames of relatively low temperature but of great heating capacity are required.

To this end my invention consists, briefly stated, in first atomizing the liquid hydrocarbon by a jet of air under pressure; second, conducting the mixture of atomized hydrocarbon and air into a primary combustion chamber and there subjecting it to a partial combustion, whereby the said atomized liquid hydrocarbon is wholly converted into gaseous products; third, in burning the combustible constituents of the gas mixture from the primary combustion in a secondary combustion chamber, or kiln shaft, by mixing therewith a mixed draft current of air and non-combustible gasses, whereby the combustible constituents of the mixture are burned with the production of a long, slow-burning flame of relatively great volume.

In the accompanying drawings I have shown in rather diagrammatic form an apparatus capable of carrying out my invention in the burning of limestone.

Figure 1 of the drawings represents a partial, vertical, diametral cross section of the apparatus, while Fig. 2 is a diagrammatic side elevation of the apparatus.

1 is the kiln shaft, 2 is the primary combustion or gasifying chamber, 3 the secondary combustion chamber, 4 the checker-work of highly refractory firebrick in the chamber 2, while 5 is a corresponding checker-work in the chamber 3. The arrangement of the combustion chambers and checkers is diagrammatic in character but is sufficient for the purpose of illustrating this specification.

6 is an "atomizing" or spraying nozzle of any approved pattern.

7 is the oil supply conduit (as shown an ordinary pipe), 8 the conduit carrying the compressed air for atomizing the oil and for supporting the primary combustion.

9 is the horizontal conduit or pipe connecting conduits 7 and 8 with the nozzle 6.

10 is a dampered inlet for air when it is not desired to compress all of the primary air and use it in the atomization of the hydrocarbon.

11 is the pipe through which the mixture of air and combustion gas (in this case an air and kiln gas mixture) is forced to sustain the secondary combustion. 12 is a valve on conduit 11.

13 and 14 are valves on the oil and air conduits, 7 and 8, respectively.

15 is the bridge wall of the furnace, 16 the grate of the same.

17 and 18 are metal plates laid on the grate and forepart of the furnace hearth. The plates 17 and 18 are laid so as to leave an open slot, 19, between them for the passage of the secondary current from the ash-pit, 20, to the chamber 3. A layer of sand, fireclay, or other refractory material 21, is spread on the plates 17 and 18 to protect them from the heat of the combustion chambers.

22 is a blower, preferably of the positive pressure type, supplying under pressure the air required to atomize the oil.

23 is a tank for storing the oil used.

24 is a blower for supplying the mixture of air and kiln gas to the secondary combustion chamber 3, while 25 is an air damper on the suction pipe 26 of the blower 24, for regulating the proportion of air in the draft current.

The air entering the furnace through the pipe 8 I will designate the "primary air", the air entering through the pipe 11 the "secondary air". The mixed current of air and non-combustible gases from 11 I will call the "secondary draft current".

The method of operating the apparatus is as follows: Air is turned on from the pipe 8 by opening the valve 14 and oil from the pipe 7. In passing through the nozzle 6 the oil is divided into a very fine mist or reduced to the so-called "atomized" condition. As it issues from the nozzle 6 the mixture of air and "atomized" oil is ignited and permitted to burn in the chamber 2. At first the air is used in excess so as to burn the oil completely in the primary chamber 2. As soon, however, as the checker-work in the

chambers 2 and 3 and the walls of the chambers have been brought up to a good working temperature—say 2000 to 2200° F.—the apparatus is in condition to carry out my process.

The primary air is gradually reduced and the secondary draft current turned on from the pipe 11. The reduction of the primary air results in the incomplete combustion of the oil in passing through 2, the unconsumed constituents being burned in 3 by the oxygen of the secondary draft current. When the primary air has been cut down to the point at which further reduction produces no further diminution in the percentage of CO₂ in the gases from chamber 2 the proper proportion of air to oil in the primary current will have been established. In practice, this point can be determined by a competent operator from the appearance of the flame in the primary combustion chamber. When normal conditions have been established the draft current passing from chamber 2 to chamber 3 will consist of gasified hydrocarbons, free hydrogen, steam, carbon monoxide and nitrogen with just as much CO₂ as is essential for equilibrium under the conditions in chamber 2. This percentage will vary more or less but I find that it is possible to so conduct the gasifying action in chamber 2 that the gases will not carry more than 5% of CO₂. Working in the manner above described I find it possible to completely gasify the hydrocarbon oil in 2 so as to produce a large proportion of permanent gases which so dilute the undecomposed hydrocarbons remaining that in the second stage of combustion I am able to effect the combustion of the gas with the production of little or no smoke.

In the burning in the second combustion chamber 3 of the gases from the primary combustion, the quantity of secondary air should be so regulated as to supply for the combustion a considerable excess of oxygen over that which is theoretically required. This excess of oxygen would, if admitted alone, produce a short intense flame with destructive results to the brickwork of the furnace. To overcome this, I mix with the air sufficient combustion gases, or gases from the limekiln itself, to so attenuate the oxygen as to materially reduce the speed of reaction in the secondary combustion chamber. In fact, I find that the flame may be prolonged into the shaft of the kiln itself. The exact proportion of combustion or kiln gases that will be required in the secondary combustion to produce this effect will depend upon the character of the gas mixture leaving the primary checker-work. This, in turn, will depend upon the nature of the oil used and upon the proportion of air to oil used in the primary combustion. Usu-

ally, the proportion of kiln gas used in the secondary current will be from 15 to 50 per cent., by volume, the remainder being free air.

By conducting the combustion of heavy oils according to my invention in the manner described above, I am able to use such fuels in furnaces, kilns, etc., requiring a low combustion temperature with the same safety and certainty of regulation as can be secured when using fuels, such as producer gas, of low calorific intensity. Besides, by so reducing the flame temperature, I do away with the rapid deterioration and burning out of the furnace walls, ironwork, etc., which invariably follows the burning of oil in the customary way and with air alone.

In addition to the above advantages, my invention possesses the important advantage that it requires no complicated apparatus for its application. Furnaces of the ordinary type in connection with lime-kilns, brick-kilns, etc., may be readily converted to use my method of combustion. Such a converted furnace is shown in the accompanying drawing.

Having described my invention, what I claim is:

1. The process of burning liquid hydrocarbons to effect decomposition of materials, which comprises, atomizing the said liquid hydrocarbons by a jet of air under pressure, conducting the mixture of atomized hydrocarbons and air into a refractory-walled chamber, subjecting the hydrocarbons of said mixture to partial combustion in said chamber to convert said hydrocarbons into combustible gases and to heat the gases produced to a comparatively high temperature, introducing into the hot combustible gases produced by said partial combustion a further portion of air diluted with gases derived from the decomposition of said materials, whereby the gases produced by said partial combustion are subjected to slow combustion, and conducting the slowly burning gaseous mixture into contact with said materials.

2. The process of burning liquid hydrocarbons to effect decomposition of materials, which comprises subjecting said hydrocarbons to the action of a jet of air under pressure, whereby the said hydrocarbons are converted into a mist uniformly disseminated throughout the said primary air, conducting the hydrocarbon laden air into contact with a mass of refractory material, subjecting the said hydrocarbon mist to partial combustion to convert the same into hot combustible gaseous products, mixing with the said hot gaseous products sufficient secondary draft current to burn substantially all combustible constituents of said gaseous products, and subjecting the resulting mix-

ture to combustion to produce a long flame of moderate temperature, the said secondary draft current comprising a mixture of air and gases derived from the decomposition 5 of said materials, the relative proportions of the said constituents of said secondary draft current being regulated to produce a flame of the length and temperature desired.

3. The process of burning liquid hydrocarbons to effect decomposition of materials, which comprises, subjecting said liquid hydrocarbons to the action of a current of primary air under pressure to convert the said hydrocarbons into a mist disseminated with 10 substantial uniformity throughout said primary air current, conducting the hydrocarbon laden air into contact with refractory material and subjecting the said hydrocarbon mist to partial combustion by said primary air to produce combustible gaseous products, the proportion of primary air to hydrocarbon being regulated to the proportion which will burn said hydrocarbon with the production of a practical minimum 15 portion of carbon dioxide in the said gaseous products, mixing with the said gaseous products an excess of secondary draft current, and burning the resulting mixture with a long flame of moderate temperature, the 20 said secondary draft current comprising a mixture of air and gases from the decomposition of said materials, the relative proportions of the said constituents of said mixture being regulated to produce the length and 25 temperature of flame desired.

4. The process of burning liquid hydrocarbons to decompose materials, which comprises, atomizing said liquid hydrocarbon with a current of primary air under pressure to produce 30 a mixture of air and atomized hydrocarbon, conducting the said mixture into contact with refractory material, subjecting the said mixture to partial combustion to produce hot combustible gaseous products, the proportion 35 of the said primary air to the said hydrocarbon being regulated to that proportion required to convert the said liquid hydrocarbon into the gaseous state, introducing into the gaseous products of the primary 40 combustion a secondary draft current, the said secondary draft current comprising a mixture in regulated proportions of air and gases from the decomposition of said materials, and subjecting the said mixture of 45 combustible gaseous products and secondary draft current to combustion in contact with 50 said materials.

5. The process of burning liquid hydrocarbons to effect decomposition of materials, which comprises, atomizing said liquid hydrocarbon with a current of air under pres-

sure to produce a primary draft current comprising a mixture of atomized hydrocarbon and air in regulated proportions, subjecting said draft current to primary combustion to produce hot combustible gaseous products, the proportion of air to hydrocarbon in said primary draft current being restricted to that proportion required to effect the substantially complete gasification of 65 hydrocarbon by semi-combustion thereof, introducing into the hot combustible gaseous products of the said primary air an excess of secondary draft current and subjecting the resulting gaseous mixture to slow 70 secondary combustion in contact, first, with heated refractory material and finally with the materials undergoing decomposition, the said secondary draft current comprising a mixture of air and gases from the decomposition 75 of said materials, the relative proportions of air to said gases of decomposition in the said secondary draft current being that proportion required to produce the speed of combustion and flame temperature desired. 80

6. The process of burning liquid hydrocarbons which comprises, atomizing said liquid hydrocarbon with a jet of primary air under pressure to produce a primary draft current comprising regulated proportions of liquid hydrocarbon and air, subjecting the said primary draft current to primary combustion in a refractory-walled region to produce hot combustible gaseous products, the relative proportion of air to 90 hydrocarbon in the said primary draft current being that proportion which will effect the complete gasification of said hydrocarbon in said primary combustion, in part by 95 partial combustion of the same and in part by vaporization of the same by heat developed by said partial combustion, introducing into and mixing with the hot gaseous products of said primary combustion an excess of a secondary draft current comprising 100 a mixture of air and non-combustible gases, and subjecting the resulting mixture to comparatively slow secondary combustion in contact first with heated refractory material and finally in heat-transferring relationship with materials to be heated, the 105 proportion of said non-combustible gases constituting from 15 to 50% by volume of the said secondary draft current, the remainder being air. 110

Signed at New York city in the county of New York and State of New York this 9th day of January A. D. 1911.
